UNITED STATES PATENT OFFICE

2,462,754

GOLF CLUB

Herbert C. Lagerblade and Donald J. Root, Bristol, Conn., assignors to The Horton Manufacturing Company, Bristol, Conn., a corporation of Connecticut

Application June 14, 1946, Serial No. 676,801

4 Claims. (Cl. 273—80)

1

The present invention relates to golf clubs of the type having metallic hosels and metallic shafts, and more particularly to the manner of interconnecting said hosels and shafts.

In accordance with the prior art, it is conventional to secure a metallic shaft to the metallic hosel of a golf club head by riveting. It is an advantage of the present invention, however, that the prior method of securing the shaft to the hosel may be eliminated and at the same time the connection between the shaft and the hosel may be improved and may be more readily formed.

The foregoing and other advantages of the invention will be apparent from the following description of a specific embodiment of the invention as shown in the accompanying drawings, in which

Figure 1 is a fragmentary front view of a golf club embodying the invention;

Fig. 2 is a fragmentary front view, partly in cross section, showing a shaft inserted into a hosel prior to deformation in accordance with the present invention;

Fig. 3 is a view similar to Fig. 2 showing the deformation of the hosel and shaft after assembly in accordance with the invention;

Fig. 4 is a cross sectional view similar to Fig. 3 with the club head rotated 90°; and

Fig. 5 is a cross sectional view taken along the line 5—5 of Fig. 1 and looking in the direction of the arrows.

Referring to the drawings, the golf club head 1 is provided with a conventional metallic hosel 2 which is slightly tapered to provide a diminishing generally circular cross section from top to bottom. The hosel 2 is formed with an axial bore 3 which similarly tapers from top to bottom.

In assembling the golf club, a tapering hollow metallic shaft 4 is inserted into the axial bore 3 to provide a driving fit. To this extent, the description also applied to conventional golf clubs of the type having metallic hosels and shafts.

In accordance with a preferred embodiment of the invention, a hardened steel ball 8 is then inserted within the hollow shaft 4 intermediate the ends of the hosel 2. The hardened steel ball 8 may be of a standard commercial type and preferably has a diameter at least as great as the inner diameter of the hollow shaft 4 at the portion 7 where it is positioned. In this step of the assembly, the ball 8 is rammed into the desired position, which, incidentally, has the effect of insuring that the wall of the shaft 4 will be in intimate contact with the wall of the hosel 2.

The hosel 2 and the shaft 4, in assembled posi-

tion, are then subjected to pressure at the portion 7 intermediate the ends of the hosel 2 where the steel ball 8 is positioned to diminish one cross sectional diameter, as shown in Fig. 3, which at the same time slightly enlarges the diameter at 90° therefrom, as shown in Fig. 4. It is preferred to accomplish this deformation so that the cross section of the deformed portion 7 intermediate the ends of the hosel 2 is generally elliptical or oval in shape.

When the hardened steel ball 8 is utilized, there is a very noticeable swaging of the walls of the shaft 4 and hosel 2 to the shape of the ball 8. This is believed to be due to the relative hardness of the steel ball 8 as compared with the metal from which the shaft 4 and hosel 2 are formed, which results in a flowing of the metal of the shaft and hosel around the ball during the squeeze operation.

The deforming of the hosel 2 and shaft 4 in accordance with the invention may be accomplished in any convenient manner. For example, the deformation has been accomplished satisfactorily in accordance with the invention by the use of a standard hydraulic press provided with the usual squeeze die.

As a precautionary measure, it may be desirable to incorporate a soft metallic billet 5 in the end of the shaft 4 before the squeeze operation. The billet 5 is preferably constructed to fit snugly into the lower end of the shaft 4 and to remain positioned there during assembly of the club. The purpose of the soft metallic billet 5 is to prevent the end of the shaft 4 from taking the same shape as the upper deformed section during the squeeze operation.

In general, the amount of deformation required to provide a permanent and secure connection between the shaft 4 and the hosel 2 is only very slight and may not even be readily apparent to the eye. For example, a conventional hosel having an outer diameter of the order of about 0.5 inch may be securely attached to the shaft by a deformation of the order of about only 0.03 to 0.04 inch out of round.

Referring to Fig. 5, it will be apparent that, as a result of the deformation, there occurs a double interlocking of the shaft 4 and hosel 2 which will effectively prevent the shaft from coming loose from the hosel. For example, the undeformed diameter of the shaft 4 above and below the oval section will be larger than the smallest diameter of the oval section. At the same time, the longest diameter of the oval section is greater than the undeformed diameter of

the axial bore 3 above and below the deformed portion 7. At the same time, the oval or elliptical cross section of the deformed portion 7 effectively prevents turning of the shaft 4 in the hosel 2.

When the hardened steel ball 8 is present, the swaging of the walls of the shaft 4 and hosel 2 to the shape of the ball 8 creates a further lock between the shaft and the hosel and thereby provides an additional safeguard against the shaft coming loose from or turning in the hosel.

The advantages of a golf club constructed in accordance with the present invention as described above will be even more readily apparent by comparison with golf clubs of the prior art in which the shaft and hosel are secured together by careful fitting of the shaft within the hosel followed by drilling, riveting and finishing. In the prior art golf clubs, extreme care must be taken to accurately fit the shaft within the hosel to avoid relative pivoting of the shaft and hosel at the rivet. In the construction of the present invention, materially less care need be taken in fitting the shaft within the hosel as the deformed portion itself effectively prevents relative movement of the shaft or hosel. The elimination of the drilling and riveting steps of the prior art also effects a material saving in time and cost in the manufacture of the golf club. In addition, as drilling and riveting are not required, there is no necessity for grinding off the end of the rivet or pin which heretofore frequently marred the finish and rendered the club unsightly. As a result, a golf club may be assembled in accordance with the present invention which not only functions in a superior manner, but at the same time may be more easily and inexpensively constructed.

Having thus described specific embodiments of the invention, it will be apparent that the device may be modified by one skilled in the art within the scope of the invention, and all such modifications are intended to be included within the scope of the following claims.

We claim as our invention:

1. In a golf club, a metallic hosel having an axial bore therein and a hollow metallic shaft fitted into said bore, said hosel and shaft being generally circular in cross section throughout but having a portion intermediate the top and bottom of the hosel which is generally oval in cross section whereby the shaft is securely fastened to the hosel.

2. In a golf club, a metallic hosel having an axial

bore therein, a hollow metallic shaft having one end fitted into said bore and a soft metallic billet of generally circular cross section positioned within said end of the hollow shaft and spaced from the top of the hosel, said hosel and shaft being generally circular in cross section throughout but having a portion intermediate the top and bottom of the hosel which is of generally oval cross section whereby the shaft is securely fastened to the hosel.

3. In a golf club, a metallic hosel having therein a tapering axial bore of generally circular cross section throughout and a tapering hollow metallic shaft of generally circular cross section throughout fitted into said bore, said hosel and shaft having a portion intermediate the ends of the hosel which is of generally oval cross section such that the smallest diameter is less than the diameter of the portions of generally circular cross section immediately above and below said portion and in which the largest diameter is greater than the diameter of the portions of generally circular cross section immediately above and below said portion.

4. In a golf club, a metallic hosel having an axial bore therein, a hollow metallic shaft fitted into said bore, and a steel ball positioned within said hollow metallic shaft intermediate the top and bottom of the hosel, said hosel and shaft being generally circular in cross section throughout but having a portion extending around said ball intermediate the top and bottom of the hosel which is of generally oval cross section, said ball having a diameter at least as great as the smallest inner diameter of said shaft at said oval portion.
